UNITED STATES PATENT OFFICE.

H. CLAY BASCOM AND FRANCIS RITCHIE, OF TROY, NEW YORK, ASSIGNEES
TO SAID BASCOM.

DESIGN FOR A HEATING-STOVE.

SPECIFICATION forming part of Design No. 15,387, dated September 9, 1884.

Application filed June 17, 1884. Term of patent 7 years.

To all whom it may concern:

Be it known that we, H. CLAY BASCOM and FRANCIS RITCHIE, citizens of the United States, residing in the city of Troy, in the county of Rensselaer and State of New York, have jointly invented and produced a new and original Design for Heating-Stoves, of which the following is a specification, reference being had to the accompanying cut, print, or engraving of a stove having said design.

This design embraces several new and distinct parts and combinations of parts, which go to make up with beneficial effect the whole design, as shown in the accompanying illustration and hereinafter specified.

The design for the vase A consists of the configuration and ornamentation of the lower part, *a*, upper portion, *b*, and the intermediate part, *c*.

20 The design for the cover B consists of the upper concavely-curved part, *d*, having the ornaments *e*, the lower band, *f*, and the intermediate convexly-curved portion, *g*, having the series of alternating ornaments *h* and *i*.

25 The design for the combustion-chamber section C embraces the curved side surface, *k*, having thereon the compound plant-form ornament *j*, the curved front surface, *m*, having the projecting door-frame, and the ornamental door *l*.

30 The design for the cylindrical fire-pot section D embraces the front and side ornamental panels, *n n'*, the row of floral ornaments *o*, the door *p*, and the ornamentations *q*.

35 The design for the base-section E consists of the configuration and ornamentation of the top *r*, front door, *s*, and the three terrace-inclines *t t' t''*.

40 The design for the legs F consists of the convexly and concavely curved surface *v*, having the floral ornament *w*, and the two lateral ornamental inclines *x x'*.

The design for the main portion of the stove
embraces the configuration and ornamentation

of the top plate, combustion-chamber section 45
C, fire-pot section D, base-section E, and the
bottom plate.

The whole design embraces the shape and
ornamentation of the vase A, cover B, the top
plate, the sections C, D, and E, the bottom 50
plate, and the legs.

We claim as new—

1. In a design for a stove, the configuration
and ornamentation of the vase A, consisting of
the parts *a b c*, as shown and described. 55

2. In a design for a stove, the shape and or-
namentation of the cover B, consisting of the
parts *d e f* and *g h i*, as shown and described.

3. In a design for a stove, the configuration
and ornamentation of the combustion-cham- 60
ber section C, consisting of the parts *k j* and
m l, as set forth.

4. In a design for a stove, the ornamenta-
tion of the cylindrical fire-pot section D, embr-
acing the parts *n n' o p q*, as set forth. 65

5. In a design for a stove, the shape and or-
namentation of the base-section E, consisting
of the parts *r s t t' t''*, as shown and described.

6. In a design for a stove, the configuration
and ornamentation of the legs, consisting of 70
the parts *v w x x'*, as shown and described.

7. In a design for a stove, the configuration
and ornamentation of the main portion, embr-
acing the top plate, the sections C, D, E,
and the bottom plate, as set forth. 75

8. The design for a stove, consisting of the
vase A, cover B, the top plate, the sections C,
D, E, the bottom plate, and the legs, all shaped
and ornamented as set forth.

In testimony whereof we hereunto set our 80
hands, in the presence of two subscribing wit-
nesses, this 14th day of June, 1884.

H. CLAY BASCOM.
FRANCIS RITCHIE.
